(57) **CLAIM**

The ornamental design for a LED light bar, as shown and described.

DESCRIPTION

FIG. 1 is a front perspective view of a LED light bar;
FIG. 2 is a right elevation view thereof;
FIG. 3 is a top plan view thereof, the bottom plan view being a mirror image thereof;
FIG. 4 is a front elevation view thereof; and,
FIG. 5 is a rear elevation view thereof.

The broken lines of equal length shown in the drawings depict portions of the LED light bar that form no part of the claimed design.

The broken lines of unequal length shown in FIGS. 1, 3-5 of the drawings represent the boundaries of the claimed design and form no part thereof.

1 Claim, 2 Drawing Sheets

FIG. 3

FIG. 4

FIG. 5
